UNITED STATES PATENT OFFICE.

WILLIAM H. BROWN, OF ALPENA, MICHIGAN, ASSIGNOR OF ONE-HALF TO
DONALD LE ROY, OF SAME PLACE.

EXCELSIOR-MACHINE.

SPECIFICATION forming part of Letters Patent No. 610,893, dated September 20, 1898.

Application filed March 15, 1898. Serial No. 673,932. (No model.)

To all whom it may concern:

Be it known that I, WILLIAM H. BROWN, a citizen of the United States, residing at Alpena, in the county of Alpena and State of Michigan, have invented new and useful Improvements in Excelsior-Machines, of which the following is a specification.

My invention relates to machines for making excelsior; and it consists in the peculiar and advantageous construction hereinafter described, and particularly pointed out in the claims appended.

In the accompanying drawings, Figure 1 is a perspective view of my improved machine complete, with one of the gear-cases partly broken away. Fig. 2 is an enlarged detail section taken in the plane indicated by the line *xx* of Fig. 1 and illustrating some parts which are omitted from Fig. 1. Fig. 3 is a transverse section taken in the plane indicated by the line *ww* of Fig. 1, with the rotary cutter in elevation. Fig. 4 is a transverse section taken in the plane indicated by the line *yy* of Fig. 1, with the feed-roll in elevation. Fig. 5 is an enlarged detail section taken in the plane indicated by the line *zz* of Fig. 1. Fig. 6 is a detail transverse section taken on the line *nn* of Fig. 5. Fig. 7 is a detail enlarged section taken in the plane indicated by the line *mm* of Fig. 3. Fig. 8 is an enlarged detail section taken in the plane indicated by the line *oo* of Fig. 1, and Fig. 9 is a detail enlarged section illustrating the manner in which the slidable journal-boxes of the movable feed-rolls are connected with the main frame and also with the inner members of toggle-levers.

In the said drawings similar letters designate corresponding parts in all of the several views, referring to which—

A designates the bed-timbers of my improved machine, and B designates parallel main frame-sections, which are preferably of cast-iron and are suitably connected to the bed-timbers. These frame-sections B are designed to receive a reciprocatory cutter-head C between them, and they are therefore provided adjacent to their opposite ends with guide-blocks *a* and slide-blocks *b*, of wood or other suitable material, the blocks *a* being

adapted to engage the sides of the cutter-head, so as to guide the same in its movements, and the blocks *b* being adapted to bear against the under side of said head and form a slide-rest for the same. The blocks *a* *b* are arranged in pockets *c* *d*, respectively, and serve to hold the reciprocatory cutter-head free from the frame-sections, and thereby prevent heating of the parts when the machine is in operation and at the same time form spaces between the cutter-head and frame-sections for the escape of dust. They also serve, as better shown in Figs. 1 and 8, to hold the cutter-head so that its upper side is flush with the upper edges of the frame-sections. This is advantageous because it enables the cutters on the head to run close to the feed-rolls presently described and make more excelsior out of the stock and also because it permits of slivers, dust, and the like being readily swept off the machine. For the purpose of taking up wear when necessary the blocks *a* *b* are backed by screws *e* *f* after the manner better shown in Fig. 8.

As better shown in Fig. 1, the cutter-head C is provided with two openings *g* at opposite sides of its middle and also with two horizontally-disposed knife-blades D and two rotary cutters E. The blades D are countersunk in the head, with their beveled cutting edges presented toward the middle thereof and overhanging the openings *g*, and they are adjustably connected to said head preferably by screws *h*, which take through their slots *i*, as illustrated. The rotary cutters E, which occupy the openings *g* in the cutter-head, respectively comprise a shaft *j* and a plurality of cutting-disks *k* and spacing-washers *l*, suitably secured on said shaft. At their ends the shafts *j* of the rotary cutters E are journaled in bearing-blocks *m*, (see Figs. 3 and 7,) which are connected by screws *n* with plates *p*, countersunk in the upper side of the cutter-head. Consequently it will be seen that said bearing-blocks *m* may be readily adjusted to take up wear of the cutter-disks and may also be disconnected from the cutter-head when it is desired to remove the rotary cutter-heads therefrom for any purpose.

As will be readily observed in Figs. 1 and 2, the horizontally-disposed cutting-blades D are arranged flush with the upper side of the reciprocatory cutter-head. This is advantageous because it permits of the blades being easily set and enables them to cut easily and smoothly and at the same time prevents them from interfering with the placement of the blocks of stock between the feed-rolls.

10 F designates the stationary feed-rolls, which are journaled in boxes q, fixed upon the frame-sections B and are arranged adjacent to the middle of the machine, and G designates the movable feed-rollers, which are 15 journaled in boxes r, movable upon the frame-sections, said boxes r being preferably connected to the frame-sections by screws s, which take through their slots t, as better shown in Fig. 9. Connected in a pivotal 20 manner to the movable journal-boxes r are the inner members u of the toggle-levers H, the outer members v of which are pivotally connected to the frame-sections B, as shown. These inner and outer members of the toggle-levers are pivotally connected at their inner ends by transverse rods w, which are provided with arms x and are connected with the frame-sections B by coiled springs y, the 25 said springs being adapted to draw the inner 30 and outer members of the toggle-levers downwardly and thereby move the movable feed-rolls toward the stationary rolls, and being also adapted to normally hold the toggle-lever members in the position shown in Fig. 35 1 and thereby enable the movable feed-rolls, in conjunction with the stationary rolls, to clamp and securely hold the blocks of stock that are to be reduced to excelsior. When 40 blocks of stock are to be interposed between the movable and stationary feed-rolls, it is necessary to raise the inner ends of the members of the toggle-levers and move the movable rolls in a direction away from the stationary rolls. To this end I provide the hand-levers I, which are fulcrumed on one frame-section and are loosely connected at one end to the arms x of the transverse rods w, as shown. When the free ends of these levers I are moved downwardly from the position 45 shown in Fig. 1, the rolls G will be moved a slight distance in a direction away from rolls F, and when said levers I are released the said rolls F will by the action of the springs y be returned to the position shown, and in 50 consequence the levers will be caused to resume their illustrated normal position. From this it follows that blocks of stock—i. e., wood—may be quickly and easily clamped between the rolls G and the rolls F 55 and that said rolls are capable of holding the blocks of stock while the same are being reduced to excelsior by the blades D and rotary cutters E of the cutter-head.

In order to prevent jar of the cutter-head 60 C and reciprocate it in a straight line, so as to enable its blades D and rotary cutters E to

cut evenly, I connect said cutter-head with the actuating-motor (not shown) through the medium of the mechanism shown in Fig. 2. This mechanism comprises a lever J, which is fulcrumed at one end, a pitman K, connected to the lever J at an intermediate point of its length and adapted to be connected with the steam-engine or other motor, and a pitman L, interposed between the opposite end 75 of the lever and the cutter-head. When the lever J is rocked to and fro by the motor, it will, through the medium of the pitman L, reciprocate the cutter-head without jar and without any tendency to move it out of a straight line.

In order to rotate the rolls F G to feed the blocks of stock down upon the knife-blades and rotary cutters of the cutter-heads, I provide mechanism intermediate of the rocking 85 lever J and the feed-rolls, as follows:

Fixed on the rolls F G at one end are gear-wheels a', and journaled in suitable bearings on one of the frame-sections B are feed-shafts b' b², each of which carries a worm-gear c', which is fixed to it, and a worm-gear c², which is connected to it by a spline, as shown, the said worm-gears c' c² meshing with the gear-wheels a' of the stationary and movable feed-rolls, respectively, and having their threads 95 pitched, as shown, so as to enable the stationary and movable feed-rolls to move the blocks of stock between them downwardly as is necessary. The worm-gears c² being connected with the shafts b' b² by splines, it follows that 100 they will turn with said shafts, and yet are free to move longitudinally upon the same when the movable feed-rolls are adjusted. In addition to the worm-gears the feed-shafts b' b² are provided with ratchet-wheels d', which 105 are keyed or otherwise fixed upon them, and arms e', which are loosely mounted upon them over the ratchet-wheels and carry dogs f', adapted to engage said ratchet-wheels, as better shown in Fig. 5. These arms e' are 110 preferably formed of steel in the manner shown in Fig. 5 and are provided in their opposite side walls with longitudinal slots g', in which rest bolts h', having a head i' at one end and their opposite ends threaded for the 115 reception of hand-wheels j', as better shown in Figs. 5 and 6. The said bolts h' are straddled by straps k', and between the ends of said straps are arranged the upper ends of pitmen l', which are pivotally connected to 120 said straps k' and are connected at their lower ends through the medium of ball-and-socket joints e² with the opposite ends of a lever m', mounted to rock in a vertical plane. On one of the trunnions of said lever m' an arm 125 n' is fixed, and between said arm and the lever J a pitman p' is interposed, as shown in Fig. 1. In virtue of this construction it will be observed that when the machine is in operation the lever m' will rock in concert with the lever J, and that in consequence the shafts b' b² will be alternately rotated in 130

the direction indicated by arrow. It will also be noted that the shaft b' will be rotated only when the cutter-head C is moving toward the right and the knife-blade D to the left is idle and that the shaft b^2 will be rotated only when the cutter-head C is moving toward the left and the knife-blade D to the right is idle. In virtue of this the downward feed of each block of stock will take place when the knife below it has left the end of the block moving backward, so as to prevent friction on the knife-blade, and each block of stock will be securely held against movement when the knife-blade below it is making a forward cutting stroke. This, as will be readily appreciated, insures uniformity in the thickness of the strips taken from the blocks of stock by the knife-blades and enables said blades to better perform their function.

When it is desired to increase or diminish the thickness of the strips taken from the blocks of stock by the knife-blades D, it is simply necessary to increase or diminish the throw of the arms e' on the feed-shafts b' b^2 . This may be readily done by adjusting the bolts h' in the slots of the arms d' , the said bolts being adjustably fixed in the arms by the hand-wheels j' , as better shown in Fig. 6.

As will be readily observed by reference to Fig. 1, the ball-and-socket joints between the pitmen l' l^2 and lever m' , the pivotal connection between said pitmen and the straps k' , and the loose connection between said straps and the bolts h' will insure a free movement of the parts no matter to what extent the bolts h' are adjusted.

For the purpose of preventing dirt and dust from getting into and interfering with the gearing the several gear-wheels on the feed-rolls are inclosed in cases M, the said cases being connected with the journal-boxes of the rolls, as best shown in Fig. 4.

Having thus described my invention, what I claim is—

1. In an excelsior-machine, the combination of a main frame, a reciprocatory cutter-head, rotary cutter-heads and oppositely-arranged cutting-blades carried by said head, stationary feed-rolls journaled in bearings fixed on the frame and carrying gear-wheels, movable feed-rolls journaled in bearings movable on the frame and also carrying gear-wheels, independent, alined feed-shafts journaled in bearings at one side of the main frame and each having a fixedly-connected worm-gear meshing with the gear-wheel of one stationary roll and a splined worm-gear meshing with the gear-wheel of one movable roll, ratchet-wheels fixed on the feed-shafts, arms loosely mounted on the shafts and carrying pawls in engagement with the ratchet-wheels, a lever fulcrumed at an intermediate point of its length, connections between the opposite ends of said lever and the arms, and a suitable means for rocking said lever, whereby the feed-shafts are alternately actuated, substantially as specified.

2. In an excelsior-machine, the combination of a main frame, a reciprocatory cutter-head, stationary feed-rolls journaled in bearings fixed on the frame and carrying gear-wheels, movable feed-rolls journaled in bearings movable on the frame and also carrying gear-wheels, feed-shafts journaled in bearings on the main frame and each having a fixedly-connected worm-gear meshing with the gear-wheel of one stationary roll and a splined worm-gear meshing with the gear-wheel of one movable roll, ratchet-wheels fixed on the shafts, arms loosely mounted on the shafts and carrying pawls in engagement with the ratchet-wheels, a lever fulcrumed at an intermediate point of its length, pitmen connected at one end to the opposite ends of the lever and having their upper ends adjustably connected to the arms on the feed-shafts whereby they may be fixed at various distances from said shafts, and a suitable means for rocking the said lever, substantially as specified.

3. In an excelsior-machine, the combination of a main frame, a reciprocatory cutter-head, on oscillatory lever connected with the cutter-head and adapted to be connected with a motor, feed-rolls journaled in suitable bearings on the main frame, two feed-shafts journaled on the main frame and each connected by gearing with two feed-rolls, ratchet-wheels fixed on said shafts, arms loosely mounted on the shafts and carrying pawls in engagement with the ratchet-wheels, a lever fulcrumed at an intermediate point of its length and having its ends connected with the arms on the feed-shafts, and a connection between said lever and the oscillatory lever, substantially as specified.

4. In an excelsior-machine, the combination of the main frame-sections having the pockets c d at intervals in their length, a reciprocatory cutter-head, of less width than the space between the frame-sections, arranged between the said sections and having its upper side flush with the upper edges thereof, guide-blocks arranged in the pockets c of the frame-sections and extending inwardly beyond said frame-sections and engaging the side edges of the cutter-head whereby the cutter-head is held free from the frame-sections and spaces formed between the head and frame-sections for the escape of dust, bearing-blocks arranged in the pockets d of the frame-sections and disposed below and forming slide-rests for the cutter-head, and adjusting-screws backing the guide and bearing blocks, substantially as specified.

5. In an excelsior-machine, the combination of a main frame, a reciprocatory cutter-head, a stationary feed-roll journaled in suitable bearings on the main frame, a movable feed-roll, bearing-boxes carrying said movable roll and adjustably connected with the main frame, a toggle-lever comprising an outer member connected with the main frame, and inner members connected to the adjust-

able bearing-boxes and pivotally connected to the outer member, a spring connected with the toggle-lever and frame and adapted to exert a downward pull on said lever, and suitable means for flexing the toggle-lever and thereby moving the movable feed-roll in a direction away from the stationary roll, substantially as specified.

In testimony whereof I have hereunto set my hand in presence of two subscribing witnesses.

WILLIAM H. BROWN.
